UNITED STATES PATENT OFFICE

CHARLES J. BIEK, OF DOWAGIAC, MICHIGAN

HOT-AIR FURNACE

Application filed May 10, 1928. Serial No. 276,542.

My improved hot air furnace is especially designed by me for the burning of gas although desirable for use with other fuels.

The main objects of the invention are:

- 5 First, to provide a hot air furnace adapted for the burning of gas which is highly efficient and one in which a high percentage of the heat units of the fuel is utilized or taken up by the air.
- 10 Second, to provide a structure of the class described which is simple and economical in its parts and the parts adapted for convenient assembly.

Objects pertaining to details and economies of the invention will definitely appear from the description to follow. The invention is defined in the claims.

A structure embodying the features of my invention is clearly illustrated in the accompanying drawings, in which:

Fig. 1 is a fragmentary perspective view of a hot air furnace embodying the features of my invention.

Fig. 2 is a detail view partially in vertical section on a line corresponding to line 2—2 of Figs. 3 and 4.

Fig. 3 is a horizontal section on line 3—3 of Fig. 2.

Fig. 4 is a horizontal section on line 4—4 of Fig. 2.

Referring to the drawings, 1 represents the casing of a hot air furnace, the hot air flues being shown at 20 and a cold air intake at 21. This is of suitable dimensions to house the furnace proper which consists of a base 2 on which a combined combustion chamber and radiator unit 3 is mounted. This combined combustion chamber and radiator unit is formed of two vertical sections having co-acting joint flanges on their meeting edges and opposed ears adapted to receive the connecting bolts.

The unit 3 is expanded upwardly and its upper portion has vertical flute-like convolutions 4 therein terminating in the dome 5. The down-draft flues 6 are formed integrally with the sections of this unit, these flues being disposed in opposed relation.

I provide an inverted conical baffle plate 7 having extensions or projections 8 extending

into the flutings into which the flues are merged and engaging supporting lugs 10 on the walls. It also has extensions 9 which engage between lugs 10 on the inwardly curved portions 11 of the walls between the flutings. Thus arranged a plurality of communicating openings 12 are provided for the combustion chamber to the radiator chamber. The edges of the sections are provided with coacting joint ribs and recesses 13 and 14.

At the lower ends of the flues I provide a horizontally disposed manifold 15 which is of segmental shape and provided with a central upwardly extending discharge flue 16. The air in circulating through the casing is brought into contact with the walls of the combustion chamber and radiator chamber, the downdraft flues, the manifold and the discharge flue.

A burner 17 provided with a plurality of tips is mounted on the brackets 18 at the lower end of the combustion chamber. The burner illustrated is a gas burner, although the structure is well adapted to an oil burner. The products of combustion are brought into intimate contact with the walls of the combustion chamber and radiator chamber and are uniformly distributed therein.

Structures embodying my invention are economical in their parts and the parts are easily assembled. Furnaces embodying my improvements are also very efficient.

Having thus described my invention what I claim as new and desire to secure by Letters Patent is:

1. The combination in a furnace, of a combined combustion chamber and radiator unit having upwardly expanding walls terminating in a dome, the upper portions of the walls having vertical flute-like convolutions therein extending into the dome, said unit having opposed integral vertical down-draft flues merging into opposed flutings and being vertically sectioned through the central plane of the flues, the sections having coacting joint flanges on their edges, the walls of the unit being provided with baffle plate supporting lugs disposed in a plane below the flue openings, an inverted conical baffle plate engaging said lugs and having projections

extending into the flutings into which said flues are merged and other projections engaging the walls between adjacent flutings whereby the baffle plate coacts with the flutings to provide a plurality of communicating openings from the combustion chamber below the baffle to the radiator chamber above the baffle, a horizontally disposed manifold connected to the lower ends of said flues, 10 and a discharge flue connected centrally to said manifold.

2. The combination in a furnace, of a combined combustion chamber and radiator unit having upwardly expanding walls terminating in a dome, the upper portions of the walls having vertical flue-like convolutions therein extending into the dome, said unit having opposed integral vertical down-draft flues merging into opposed flutings and being vertically sectioned through the central plane of the flues, the sections having coacting joint flanges on their edges, the walls of the unit being provided with baffle plate supporting lugs disposed in a plane below the flue openings, and an inverted conical baffle plate engaging said lugs and having projections extending into the flutings into which said flues are merged and other projections engaging the walls between adjacent flutings 30 whereby the baffle plate coacts with the flutings to provide a plurality of communicating openings from the combustion chamber below the baffle to the radiator chamber above the baffle.

35 3. The combination in a furnace, of a combined combustion chamber and radiator unit having upwardly expanding walls terminating in a dome, the upper portions of the walls having vertical flue-like convolutions 40 therein extending into the dome, said unit having integral vertical down-draft flues merging into opposed flutings a baffle plate having projections extending into the flutings into which said flues are merged and 45 other projections engaging the walls between adjacent flutings whereby the baffle plate coacts with the flutings to provide a plurality of communicating openings from the combustion chamber below the baffle plate 50 to the radiator chamber above the baffle, a horizontally disposed manifold connected to the lower ends of said flues, and a discharge flue connected centrally to said manifold.

4. The combination in a furnace, of a combined combustion chamber and radiator unit having upwardly expanding walls terminating in a dome, the upper portions of the walls having vertical flue-like convolutions therein extending into the dome, said unit having 60 integral vertical down-draft flues merging into opposed flutings, and a baffle plate having projections extending into the flutings into which said flues are merged and other projections engaging the walls between adjacent flutings whereby the baffle plate coacts

with the flutings to provide a plurality of communicating openings from the combustion chamber below the baffle plate to the radiator chamber above the baffle.

In witness whereof I have hereunto set my 70 hand.

CHARLES J. BIEK.
